PROTECTIVE EYESHIELD

Henry M. Richardson and Wesley S. Larson,
Springfield, Mass., assignors to De Bell & Richardson, Inc., Springfield, Mass., a corporation of Massachusetts

Application March 3, 1948, Serial No. 12,734

5 Claims. (Cl. 2—14)

1

This invention relates to eye shields of the type used to protect the eyes of industrial workers, combat soldiers, and others from dust, and other foreign matter.

Eye shields heretofore available for the above purposes have been bulky and cumbersome, could not be comfortably worn over the usual prescription eye glasses, and, because of the materials employed, were subject to deterioration with age and to attack by fungi. It is highly desirable that shields of this type be sufficiently flexible to fit closely around the face and forehead. To secure this advantage it has been proposed to make the protectors of sheet rubber, either natural or synthetic, and of materials such as plasticized polyvinyl chloride or polyvinyl butyral. These materials however are so non-absorbent of moisture that closely fitting protectors formed of these materials are uncomfortable and subject to fogging from perspiration. As a result either ventilation openings must be provided which destroys, at least in part, the advantages gained by a close fit, or absorbent pads must be used which adds to the bulk and stiffness of the protector and results in discomfort to the wearer.

The principal object of the present invention is to overcome the above difficulties and provide an eye shield of one-piece molded construction with lenses bonded into the frame, which gives substantially full visibility in all directions, and which can be folded flatly into pocket carrying size.

Other and further objects will be made apparent in the following specification and claims.

In the accompanying drawing:

Fig. 1 is a plan view of an eye protector embodying our invention, unfolded in flat form;

Fig. 2 is a view of the eye protector of Fig. 1 folded for pocket carrying;

Fig. 3 is a sectional view substantially on line 3—3 of Fig. 1;

Fig. 4 is a generally perspective view on a larger scale showing the eye protector of Fig. 1 set up for use; and

Fig. 5 is a fragmentary detail view showing an alternative formation of the cuts 8.

We have found that a flexible polyamide can be molded in sufficiently thin cross section to give the desired structural features later pointed out and that this material will pass moisture quite readily.

A polyamide molding composition which we have found to be suitable for our purpose is one with a low modulus of elasticity (of the order of 30,000 lbs. per sq. in.), a softening point not

2

substantially above 150° C. and with a rather broad melting range. Polyamides of this type are made commercially from co-condensations of the following three ingredients:

1. Hexamethylene diammonium adipate,
2. Hexamethylene diammonium sebacate, and
3. ϵ -Aminocaproic acid,

commercially available examples being the grades of nylon known as FM-4 or FM-8001 produced by E. I. du Pont de Nemours & Co., Inc.

For the lenses we use a clear film of ethyl-cellulose, cellulose acetate, cellulose propionate, cellulose butyrate or acetate butyrate, or other transparent flexible plastic film with or without a surface coating to improve the scratch resistance. If desired the films may be tinted with a suitable pigment.

Referring to the drawings the eye shield is 20 molded in flat thin form as generally shown in Fig. 1. The shield comprises a visor member 1, upper frame members 2, nose frame members 3, side members 4 and lower frame members 5. The visor member is divided centrally by a shallow channel 6 which extends downwardly between the nose frame members 3. A similar channel 7 intersects the channel 6 and defines the lower or forward edge of the visor member 1. In addition to other functions, later described, the channels 6 and 7 "quarter" the shield and provide hinge lines about which the shield when in flat form 25 may be folded as in Fig. 2 for easy carrying in a pocket.

The side edges of the visor member are 30 extended downwardly beyond the ends of channel 7 in the form of cuts 8 the lower ends of these cuts terminating closely adjacent the lens openings at a point below the level of the upper frame portions 2. The cuts 8 need not extend completely through the material as shown in Fig. 1, since for some purposes it may be desirable to connect their edges with a fine membrane of the material as indicated at 8' in Fig. 5.

The edges of the lens opening are channeled 35 as at 9 to receive the flexible transparent lenses 10 which are cemented or otherwise secured in place.

The upper edge portion of the visor member is feathered to a thin edge as indicated at 11 40 and the lower edge portions of the side members 4 and of the lower frame members 5 are similarly feathered to a thin edge as indicated at 12. Preferably the body of the shield has a thickness of approximately .028 of an inch, the material 45 being thinned to approximately .004 of an inch 50

at the bottom of the grooves, or to a degree which provides folding flexibility along the groove.

The side members 4 are respectively provided with the post members 13 and 14 of a snap fastener, the corresponding socket members 15 and 16 of which are carried by the adjacent upper corners of the visor member. The side members are also provided with molded sockets 17 in which the ends of a suitable elastic band 18 are secured in any suitable manner.

When in use the flat eye shield is "set up" by swinging the side members 4 substantially 90° to bring the snap fasteners 13-15 and 14-16 into engagement as shown in Fig. 4.

It will be noted that when thus set up the edges of the shield in contact with the face of the wearer are comprised entirely of the feathered edge portions 11 and 12 which, because of their extreme flexibility conform to the contours of the face of the wearer and provide a close dust-proof fit without discomfort and, because of the ability of the material to pass moisture, without danger of fogging.

The stiff visor member 1 holds the lens carrying portions rigidly away from the face permitting the wearing of prescription glasses within the protector without discomfort or disarrangement of the prescription glasses. The straight channel 7 permits the front lens portion to assume a substantially vertical position with the portions of the lenses carried by the side members 4 sharply but smoothly curved through substantially a right angle thus securing substantially a full 100% vision through the shield.

It will further be noted that the relatively stiff unfeathered portions of the side members 4 underlie the unfeathered end portions of the visor, thus reenforcing and stiffening the set up structure closely adjacent the closed ends of the cuts 8 with the result that the shaping of the shield takes place and is concentrated about the closed ends of said cuts as centers assuring ample space within the shield at the outer ends. Since the ends of cuts 8 about which the shaping is centered are positioned below the groove 1 the visor remains relatively flat and there is no objectionable "cone" formed at the center of the lenses. The channel 6 permits a slight bowing of the visor at its center to accommodate movement of the side members 4 toward each other as the shield conforms itself to the contour of the face of the wearer.

The elastic band 18 serves to hold the shield in position in an obvious and well known manner.

What we claim is:

1. An eye shield constructed in flat unitary sheet form and including a visor member, lens carrying members and side members extending from the lens carrying members, the visor member being separated from the lens carrying members by a channel forming a hinge line, the adjacent ends of the visor and side members being separated by cuts extending below the ends of said channel, said side members being bendable through an arc of substantially 90° about the closed ends of said cuts as centers to position the adjacent portions of the visor and end members in superposed relation, and snap fastener members carried by said superposed portions of the visor and end members and engageable to releasably hold said members in superposed position.

2. An eye shield constructed in flat unitary sheet form and including a visor member, lens

carrying members and side members extending from the lens carrying members, the visor member being separated from the lens carrying members by a channel forming a hinge line, a second channel at right angles to the first channel and extending across the visor member and between the lens carrying members forming a hinge line at right angles to the first mentioned hinge line, the adjacent ends of the visor and side members being separated by cuts extending below the ends of said channel, said side members being bendable through an arc of substantially 90° about the closed ends of said cuts as centers to position the adjacent portions of the visor and end members in superposed relation, and snap fastener members carried by said superposed portions of the visor and end members and engageable to releasably hold said members in superposed position.

20 3. An eye shield of flexible plastic molded in a flat unitary thin sheet form and including a visor member, lens carrying members and side members extending from the lens carrying members, the visor member being separated from the lens carrying members by a channel forming a hinge line, the adjacent ends of the visor and side members being separated by cuts extending below the ends of said channel, the upper edge portion of the visor member and the lower edge portion of the lens carrying and side members being feathered, said side members being bendable through an arc of substantially 90° about the closed ends of said cuts as centers to position the unfeathered edge portions of the side members beneath the unfeathered end portions of the visor, with the ends of said feathered edge portions of said visor and side members overlapping to form a complete feathered edge around the shield where it contacts the face of the wearer, and snap fastener members carried by the superposed portions of the visor and end members and engageable to releasably hold said members in superposed position.

40 4. An eye shield formed of a polyamide having a low modulus of elasticity, molded in a flat unitary thin sheet form and including a visor member, lens carrying members and side members extending from the lens carrying members, the visor member being separated from the lens carrying members by a channel forming a hinge line, the adjacent ends of the visor and side members being separated by cuts extending below the ends of said channel, the upper edge portion of the visor member and the lower edge portions of the lens carrying and side members being feathered, said side members being bendable through an arc of substantially 90° about the closed ends of said cuts as centers to position the unfeathered edge portions of the side members beneath the unfeathered end portions of the visor, with the ends of said feathered edge portions of said visor and side members overlapping to form a complete feathered edge around the shield where it contacts the face of the wearer, and snap fastener members carried by the superposed portions of the visor and end members and engageable to releasably hold said members in superposed position.

50 5. An eye shield formed of a flexible organic plastic, said plastic comprising the co-condensation product of hexamethylene diammonium adipate, hexamethylene diammonium sebacate, and aminocaproic acid, molded in a flat unitary thin sheet form and including visor, lens carrying and side forming portions, the edges of the

sheet being shaped to provide a close substantially air-tight engagement with the face of the wearer, the said sheet having a thickness of approximately .028 of an inch to thereby provide a moisture vapor transmission rate through the plastic sheet adequate to prevent a fog producing moisture accumulation within the shield in the absence of ventilating openings.
